HAIR COMBING, CLEANING, AND TRAINING
DEVICE

Arthur C. Scheithe, Chicago, Ill.

Application July 13, 1949, Serial No. 104,437

10 Claims. (Cl. 132—19)

1

This invention relates to hair combing devices and more particularly to combine hair combing, cleaning and training devices, although certain features thereof may be employed with equal advantage for other purposes.

It contemplates more especially the provision of a combined comb and metallic blade member associated therewith to firmly tension the hair in a series of combing strokes to clean, train, and impart a sheen thereto for the purpose of providing a better hairdo for both men and women, it being understood that it could have application to the hairdress of animals such as dogs in a modified construction for application to hair that is coarser than human hair.

Combs made from synthetics have been more or less universally used for many years, and it has served its purpose as a combing device with more or less satisfaction. With hair that is difficult to train or which is necessary of brushing after combing, the comb by itself is not too satisfactory. Consequently, individuals have resorted to water, hair dressing, hair curling fluid and a variety of other substances to assist the comb in providing the desired hairdo. Such substances are not entirely beneficial in that they attract foreign substances such as dirt, impart a greasy appearance to the hair, and have been construed as a detriment to the continued growth of hair. In large or industrial cities where there is a great proportion of foreign substances such as dirt and dust in the air, the hair becomes imbedded with these particles to such a degree that the ordinary comb is not effective in the removal thereof. This means that the individual in large or industrial cities resorts to hair washing and shampoo treatments in order to rid his hair of most foreign substances.

With the teachings of the present invention, the comb is rendered more effective to perform its usual function as well as to cleanse, train hair, stimulate the hair roots, and invigorate the growth of hair. This has been accomplished by detachably associating a highly flexible blade with the standard comb so that the latter will serve as a guide for the former, and all foreign substances including short hairs which are in abundance after a haircut will be removed while simultaneously imparting a sheen to the hair that improves the appearance and the texture thereof. This can be accomplished without any hair washing or shampooing treatments to the end that a great deal of expense, time, and inconvenience is eliminated with devices embodying features of the present invention.

2

One object of the present invention is to simplify the construction and improve the operation of devices of the character mentioned.

Another object is to provide an improved and simplified combined comb and blade that will cooperate to comb, cleanse, and train hair without resort to extraneous expedients.

Still another object is to provide an improved combing blade that is associated with a comb of standard construction serving as a guide therefor in more effectively combing, cleansing, and stimulating hair training and growth.

A further object is to provide a highly flexible blade in conjunction with a standard comb which serves as a guide therefor in imparting sheen to the hair and removing all foreign substances therefrom including short hairs and the like.

A still further object is to provide a highly flexible blade having a serrated edge for detachable association with a comb serving as a guide therefor in combing, cleansing, removing foreign substances, and training the hair, thereby providing a more effective hairdo without resort to extraneous substances such as fluids and greases.

Still a further object is to provide a finely serrated and highly flexible blade in detachable association with a comb for more effectively treating the hair in accomplishing the desired combing, cleansing, training, and other functions incident to a completely satisfactory hairdo.

Other objects and advantages will appear from the following description of an illustrative embodiment of the present invention.

In the drawing:

Figure 1 is a side view in elevation of a combination comb and blade embodying features of the present invention.

Figure 2 is a bottom edge plan view of the combination comb and blade shown in Figure 1.

Figure 3 is a side view in elevation of the blade apart from the comb.

Figure 4 is a bottom edge plan view of the blade shown in Figure 3.

Figure 5 is a bottom edge plan view of the blade attaching clip or retainer for detachably associating the blade with the comb.

Figure 6 is a sectional view in elevation taken substantially along line VI—VI of Figure 1.

Figure 7 is a fragmentary illustration of a man's head of hair showing the use of the device illustrated in Figures 1 and 2.

The structure selected for illustration is not intended to serve as a limitation upon the scope or teachings of the invention, but is merely illustrative thereof. There may be considerable vari-

ations and adaptations of all or part of the teachings depending upon the dictates of commercial practice. The present embodiment comprises an elongated standard comb 10 of limited flexibility that is made from synthetic compositions such as phenols or other suitable plastics to provide a reinforcing rib or shank 11 along the top edge thereof. The elongated rib or shank 11 tapers from the small and narrow end 12 to the large or wide edge 13 where the thickness thereof is considerably greater or substantially twice the thickness at the thin end 12.

The top rib or shank 11 of the comb 10 terminates in convexly curved end teeth 14-15 that project almost normal to the back or shank edge 16 that tapers from the thin and narrow end 12 to the thick and wide end 13. A plurality of intermediate comb teeth 17-18 of comparatively different coarseness and size project from the rib or shank 11, and these along with the end teeth 14-15 terminate in a straight line to provide more or less pointed teeth tips 19. The fine teeth 17 are formed integral with the shank 11 for substantially one-half of its length from the narrow and thin end portion 12 while the comparatively coarser teeth 19 are formed integral with the shank 11 for the remaining thicker portion extending from the thick and wide end 13 thereof.

A highly flexible and comparatively narrow tempered spring steel elongated blade 20 which is slightly narrower than the length of the small end tooth 14, is sized for application flat against the fine teeth 17 of the comb 10. The highly flexible blade 20 is substantially rectangular in configuration except for the curved end corner 21 thereof to conform with the comb end 12, and it terminates in an elongated shank 22 which is narrower than the blade 20 and substantially the same in length to provide an expedient for detachably associating the blade 20 with the comb 10 as will appear more fully hereinafter.

An elongated tubular blade shank retainer or clip 23 is provided for wedging action along the tapered rib or shank 11 of the comb 10.

To this end, the clip 23 is rolled from metallic sheet material to present an elongated cylindrical member which is spaced at its confronting edges 24-25 to provide a tapered slot 26 conforming in dimensional outline substantially to the shape and taper of the comb rib or shank 11 so that there will be a wedging action as the clip or retainer 23 is displaced along the comb rib 11 from the thin end 12 toward the comparatively thicker end 13 with the blade 20 and its extension 22 disposed adjacent the rib or shank 11 of the comb 10 with the clip 23 riding over both. This will cause the clip 23 to wedge the comb 10 and the blade 20 together for the extent of the blade extension or shank 22 so that the blade 20 is capable of free flexing for reasons which will appear more fully hereinafter. With this arrangement, the blade 20 can be placed on either side of the comb 10 for left or right hand use with the blade 20 extending in alignment with the tapered rib edge 16 and the thin and narrow end 12 of the comb 10. In this position, the retainer extends substantially for the entire length of and in confronting relation with the blade extension or shank 22.

It is to be noted that the lower edge of the blade 20 has a fine serration 27 therealong to more or less accommodate the individual hair strands and to scrape the exposed surface of the individual strands to impart the desired combing tension thereon while being displaced

along the length of the strands. The hair 28 on the head or a human 29 is placed under substantially greater tension than is possible with the use of the comb 10 alone so that the displacement of the latter with the blade 20 thereover will exert a scraping action of considerable extent and force. To this end, the blade 29 is preferably chrome plate to provide an ultra smooth surface between the serrations 27 for imparting a sheen to the hair as the comb 10 guides the blade 20 along the individual hair strands 28.

To provide the desired tension, the assembled unit is first grasped with the clip 23 in the palm of the user's hand and the smaller end portion 15 of the comb 10 with the fine teeth 17 lying substantially flat against the scalp with sufficient downward pressure exerted thereon to impart noticeable transverse flex or bowing to the blade 20 (Figure 7). As the teeth 17-18-19 of the comb 10 traverse through the hair strands 28, the trailing portion of the strands 28 become displaced between the comb teeth 17-18-19 and impinge against the unanchored portion of the blade 20 which is thus flexed and spring urged against the hair strands 28 to tension and impart a sheen thereto. Then the comb 10 with the blade 20 is drawn along the hair surface in the direction of intended combing to exert substantial tension on the individual hair strands 28. In so doing and in continuing the displacement of the comb 10 with the blade 20 in a transversed curved or flexed or bowed position owing to the downward pressure maintained thereon, the hair strands 28 will be pulled straight and scraped with a considerable degree of pressure exerted thereon to the end that the hair 28 acquires a sheen that is significantly similar to that acquired with certain hair shampoos and dressings. This tension exerted on the hair 28 with the aid of the flexing of the combing member 10 and blade 20 serves to train such along the lines that heretofore has only been possible with an extremely hard hair brush, but with far more effective cleansing owing to the shallow fine individual hair strand engaging serrations 27. By providing a more flexible blade 20 than combing member 10, a different tension can be applied by selecting a comb 10 of different degrees of flexibility without changing the blade 20 which can be the same for different hair textures. The blade 20 will conform to the flexing of the comb 10. This action removes all short hairs from the hair strands 28 after the usual hair cut is performed thereon. The hair strands 28 are stretched so that when released of their tension, they will become wavy, the hair roots are stimulated, and there is an invigorating action which should promote the growth of hair after the continued combing treatment over an extended period of time.

With a device of this character, the blade 20 can be readily removed by displacing the retainer or clip 23 toward the thin end 12 of the comb 10 to remove all collected dirt and to maintain the comb 10 with its blade 20 in a sanitary condition at all times. It should be noted that when the device is utilized on animals or individuals having an extremely coarse hair, the serrations 27 will undoubtedly be coarser than those illustrated and this should not be construed as a limitation upon the invention or its adaptations or uses.

While the highly flexible blade 20 is shown applied to a standard comb of comparatively less flexibility, yet it should be observed that

special combs may be provided depending upon the texture of the hair that is to be combed therewith and the particular uses to which the structure is put. With the use of this device, the hair is cleaned of dandruff, its texture is improved, a much more attractive sheen is imparted thereto, and the most difficult and unwieldy hair can be more or less promptly trained to give results even more effective than those heretofore acquired with the use of a standard comb and a hair brush.

While I have illustrated and described a preferred embodiment of this invention, it must be understood that the invention is capable of considerable variation and modification without departing from the spirit of the invention. I, therefore, do not wish to be limited to the precise details of construction set forth, but desire to avail myself of such variations and modifications as come within the scope of the appended claims.

I claim:

1. In a device of the character mentioned, the combination with a non-metallic hair combing member, of a comparatively more flexible flat metal blade member associated with said combing member adjacent its teeth, and a fine shallow serrated edge on said metal blade for effective frictional engagement with individual hair strands to scrape, cleanse, train, and shine the hair strands as said combined combing and metal blade members are displaced in combing movements through the hair of an individual so that the hair strands transversely flex said blade member away from said combing member teeth to exert an urge on the trailing hair strands.

2. In a device of the character mentioned, the combination with a hair combing member possessed of some transverse flexibility, of a flat blade member of comparatively much greater flexibility than said combing member, said flat blade member being associated with said combing member to lie adjacent its teeth, and a fine shallow serrated edge on said metal blade for effective frictional engagement with individual hair strands to scrape, cleanse, train, and shine the hair strands as said combined combing and metal blade members are displaced in combing movements through the hair of an individual so that the hair strands transversely flex said blade member away from said combing member teeth to exert an urge on the trailing hair strands.

3. In a device of the character mentioned, the combination with a hair combing member, of a flat blade member detachably associated with said combing member, and a shallow finely serrated edge on said metal blade for effective frictional engagement with individual hair strands to scrape, cleanse, train, and shine the hair strands as said combined combing and metal blade members are displaced in combing movements through the hair of an individual so that the hair strands transversely flex said blade member away from said combing member teeth to exert an urge on the trailing hair strands.

4. In a device of the character mentioned, the combination with a hair combing member possessed of some transverse flexibility, of a flat blade member of comparatively much greater flexibility than said combing member, said flat blade member being detachably associated with said combing member to lie adjacent its teeth, and a shallow finely serrated edge on said metal blade for effective frictional engagement with

individual hair strands to scrape, cleanse, train, and shine the hair strands as said combined combing and metal blade members are displaced in combing movements through the hair of an individual so that the hair strands transversely flex said blade member away from said combing member teeth to exert an urge on the trailing hair strands.

5. In a device of the character mentioned, the combination with a hair combing member, of a flat blade member associated with said combing member, means for detachably associating said flat blade member adjacent the teeth of said combing member, and a shallow finely serrated edge on said metal blade for effective frictional engagement with individual hair strands to scrape, cleanse, train, and shine the hair strands as said combined combing and metal blade members are displaced in combing movements through the hair of an individual so that the hair strands transversely flex said blade member away from said combing member teeth to exert an urge on the trailing hair strands.

6. In a device of the character mentioned, the combination with a hair combing member, of a flat blade member associated with said combing member, clip means for detachably wedging said flat blade member adjacent the teeth of said combing member, and a shallow finely serrated edge on said metal blade for effective frictional engagement with individual hair strands to scrape, cleanse, train, and shine the hair strands as said combined combing and metal blade members are displaced in combing movements through the hair of an individual.

7. In a device of the character mentioned, the combination with a hair comb having a reinforcing rib along an edge thereof, of a metal comparatively more flexibly flat blade disposed adjacent the combing teeth of said comb to present a hair friction engaging edge therealong, and a blade retainer clip displaceable over said comb reinforcing rib to wedge and retain said metal blade against certain of said teeth of said comb for effective frictional engagement with individual hair strands to scrape, cleanse, train and shine the hair strands so that the hair strands transversely flex said blade member away from said combing member teeth to exert an urge on the trailing hair strands.

8. In a device of the character mentioned, the combination with a hair comb having a tapered reinforcing rib of varying thickness along an edge thereof, of a comparatively flexible blade disposed adjacent the combing teeth of said comb to present a hair friction engaging edge therealong, and a blade retainer clip having a slit or opening of varying width displaceable over said comb reinforcing rib to wedge and retain said flexible blade against certain of said teeth of said comb for effective frictional engagement with individual hair strands to scrape, cleanse, train and shine the hair strands.

9. In a device of the character mentioned, the combination with a slightly flexible hair comb having a reinforcing rib along an edge thereof, of a highly flexible metal blade disposed adjacent the combing teeth of said comb to present a hair friction engaging edge therealong, and a blade retainer clip displaceable over said comb reinforcing rib to wedge and retain said flat blade against certain of said teeth of said comb for effective frictional engagement with individual hair strands to scrape, cleanse, train and shine the hair strands so that the hair strands transversely flex said blade member away from said combing

member teeth to exert an urge on the trailing hair strands.

10. In a device of the character mentioned, the combination with a slightly flexible hair comb having a reinforcing rib along an edge thereof, of a highly flexible metal blade disposed adjacent the combing teeth of said comb, a shank extending from said blade, and a blade retainer clip displaceable over said comb reinforcing rib to wedge and retain said metal blade shank against certain of said teeth of said comb for effective frictional engagement with individual hair strands, said metal blade having a serrated edge to scrape, cleanse, train and shine the hair strands.
